(57) **CLAIM**

The ornamental design for a face mask and hat for use with same, as shown and described.

DESCRIPTION

FIG. 1 is a front perspective view of a face mask and hat for use with same, showing my new design.

FIG. 2 is a front elevation view thereof.

FIG. 3 is a right side elevation view thereof.

FIG. 4 is a left side elevation view thereof.

FIG. 5 is a rear elevation view thereof.

FIG. 6 is a top plan view thereof; and,

FIG. 7 is a bottom plan view thereof.

The broken lines showing the person's face, neck and shoulders in FIG. 1 are for the purpose of illustrating environmental matter and form no part of the claimed design.

The Crosshatched pattern, although shown intermittently, is distributed uniformly over the surfaces of the claimed design and represents material.
